UNITED STATES PATENT OFFICE

JACOB LIGINSKI, OF MONTVILLE, NEW JERSEY

FIGURE TOY

Application filed June 17, 1931. Serial No. 545,110.

This invention relates to an improved figure toy of a type comprising a horizontally disposed wheel supported frame, means for accommodating a pull cord, and a mechanically shiftable figure toy on said frame.

My primary aim is to generally improve upon figure toys by providing a novel contribution to the prior art possessed of captivating and amusing abilities and therefore 10 susceptible of provoking considerable amusement for child owners.

In adopting a structure to fulfill the requirements of my inventive conception I have found it expedient and practical to 15 utilize the wheeled frame as a sort of a track and to mount thereon the base on which the toy is carried, there being an operating connection between said base and one of the rear wheels whereby the entire figure is 20 shifted back and forth as the wheeled carriage is drawn along a supporting surface.

The explicit details elected for accomplishing the desired results will become more 25 readily apparent from the following description and drawings.

In the drawings:

Figure 1 is a side elevation of a figure toy representing the preferred embodiment of this invention.

30 Figure 2 is a top plan view thereof with the figure removed.

Figure 3 is a cross section on the line 3—3 of Figure 2.

The wheeled carriage comprises a pair of 35 front wheels 4 and a pair of companion rear wheels 5. The wheels 4 are mounted on the bight portion 6 of an elongated U-shaped frame whose spaced parallel side arms are distinguished by the numeral 7. These arms 40 terminate in eyes 8 which embrace the rear wheel axle 9. Incidentally the axle carries stop rings or collars at 10 to insure proper spacing of the frame arms as well as to confine the wheels 5 appropriately in place.

45 The numeral 11 designates a front hitch formed from a single length of wire bent upon itself to provide a bail 12 whose arms terminate in eyes 13 embracing the bight 6 of the wire frame. The bend of this bail is twisted as at 14 to form an attaching loop

or eye to which the pull cord (not shown) is attached. This constitutes the propulsion means for drawing the carriage along over the pavement or other supporting surface.

The figure toy is here represented as a 55 miniature horse and denoted by the numeral 15. This is attached to and supported from a shiftable platform or base 16. In fact, the base has on its bottom eye screws 17 slideable along the arms 7. Thus the arms 7 constitute a track on which the base is longitudinally shiftable.

The operating means for the base comprises a pitman rod 18 pivoted at its front end as at 19 to one edge of the base and eccentrically pivoted at 20 to the peripheral portion of one of the rear wheels 5.

It is obvious that with this arrangement when the carriage is drawn along the surface 70 the entire figure and its supporting platform is shifted back and forth in a reciprocatory manner, the reciprocatory action being accomplished by the rotation of the rear wheel 5 and the operating connection between said wheel and platform. The assembly is such as 75 to produce a smooth and amusing shifting operation of the figure toy.

It is thought that the description taken in connection with the drawings will enable a 80 clear understanding of the invention to be had. Therefore, a more lengthy description is thought unnecessary.

While the preferred embodiment of the invention has been shown and described it is 85 to be understood that minor changes coming within the field of invention claimed may be resorted to if desired without departing from the spirit and scope of the appended claims.

I claim:

1. A figure toy comprising a horizontal U-shaped frame having its arms terminating in bearing eyes, an axle mounted for rotation in said eyes, wheels carried by said axle, 95 front wheels attached to the front portion of the frame, a platform shiftable on the intermediate portions of the arms of said frame, a pitman rod eccentrically connected with one of said rear wheels and pivotally con- 100

nected with an adjacent edge of the platform.

2. A figure toy comprising a horizontal U-shaped frame having its arms terminating in bearing eyes, an axle mounted for rotation in said eyes, wheels carried by said axle, front wheels attached to the front portion of the frame, a platform shiftable on the intermediate portions of the arms of said frame, a pitman rod eccentrically connected with one of said rear wheels and pivotally connected with an adjacent edge of the platform, a figure carried by said platform, a hitch device comprising a bail having a cord attaching loop and eye equipped arms, the eyes of said arms being pivotally connected with the bight portion of said frame.

3. In a figure toy comprising a horizontally elongated frame having its arms terminating in bearing eyes, an axle mounted in said eyes, stops on the intermediate portion of said axle engageable with the inner sides of the eyes, wheels mounted on the outer end portions of the axle beyond said eyes, a platform disposed above the frame and provided on its underside with guide eyes and slideable on the arms of said frame, a figure carried by said platform, a pitman rod pivotally connected with one longitudinal edge of the platform and eccentrically and pivotally connected with an adjacent rear wheel, a pair of front wheels mounted for rotation on the bight portion of the frame, and a hitch device swingably mounted on said bight portion and straddling said front wheel.

In testimony whereof I affix my signature.
JACOB LIGINSKI.
